UNITED STATES PATENT OFFICE

FRED H. LYNDS, OF NORTH ATTLEBORO, MASSACHUSETTS, ASSIGNOR TO WHITING & DAVIS COMPANY, OF PLAINVILLE, MASSACHUSETTS, A CORPORATION OF MASSACHUSETTS

MESH MACHINE

Application filed December 12, 1931. Serial No. 580,603.

This invention relates to the manufacture of link mesh fabric and of articles made therefrom. More particularly, the invention is concerned with a novel machine for removing links from mesh fabric of the fish-scale variety, so that the fabric may be readily cut into pieces suitable for use in the manufacture of ladies' hand bags and similar articles.

10 Fish-scale mesh, as commonly made, is composed of rings and links of generally cruciform shape, sometimes referred to as spiders, and each spider has four legs, each of which extends through a ring and is bent 15 back toward the middle of the spider on the underside of the fabric. Each spider is thus connected to four different rings in the mesh, and each ring receives the legs of four different spiders. In a flat piece of the mesh, 20 there are alternate rows of rings and spiders extending in one direction and alternate rows of rings and spiders extending at right angles to the first rows, while each bias row is made up of rings and spiders in alterna- 25

In the manufacture of articles such as hand bags from this type of mesh, it has been the practice heretofore to perform by hand all operations necessary to obtaining small 30 pieces of mesh of the desired shape and size from the larger web. For that purpose, the operative laid the mesh upside down on a flat surface, located the spiders to be removed by counting along the rows, bent back 35 the legs of the selected spiders so that they would pass through their rings, and thus removed the spiders. If the spiders were thus removed from a row made up entirely of spiders, the web was separated into two 40 pieces, but if the spiders were removed from bias rows, the remaining rings had to be cut by shears to complete the operation. The cutting of mesh fabric by these hand methods is slow and expensive and it adds substantially to the cost of the final product.

The present invention is accordingly directed to the provision of a novel machine by which the spiders can be removed from a piece of fish-scale mesh, the machine performing its functions at a high rate of speed,

removing the spiders cleanly, and in no way doing injury to links other than those to be removed.

In the new machine, the piece of mesh to be cut is fed forward face down on a suitable support, the mesh being advanced with a step by step movement. At each period of rest in the movement, a spider to be removed is brought into registry with a pair of cooperating tools and one tool then moves toward the mesh and holds it firmly against the support, the tool engaging the mesh at spaced points around the spider to be removed and holding the mesh firmly against movement relative to the support. The second tool then moves toward the spider to be removed, deforms it in such manner as to spread its legs apart to a considerable extent, and is then retracted. Thereafter, a movable portion of the holding tool is actuated to engage the deformed 60 spider and force it out of the mesh. The combined holding and ejecting tool then moves back to its original position, the mesh is advanced another step, and the cycle of operations is repeated.

The new machine may be employed for cutting the fabric lengthwise, transversely, or on the bias, the latter operation being that commonly employed. When spiders are removed from the mesh along bias lines, the 80 operations are completed by cutting the rings by hand, but this is simple and easy and in no way comparable with manual removal of the spiders.

For a better understanding of the invention, reference may be had to the accompanying drawings in which

Fig. 1 is a view of the machine of the invention in side elevation with certain parts broken away;

Fig. 2 is an end view of the machine;

Fig. 3 is a sectional view on the line 3—3 of Fig. 1;

Fig. 4 is a section on the line 4—4 of Fig. 3;

Fig. 5 is an enlarged sectional view showing the operation of certain parts of the removing tools;

Fig. 6 is a developed plan view illustrating the operation of the tools;

Fig. 7 is a developed plan view of a portion of the mesh support;

Fig. 8 is a sectional view on the line 8—8 of Fig. 7;

Fig. 9 is a longitudinal sectional view through one of the tools;

Fig. 10 is an end view of the tool shown in Fig. 9;

Fig. 11 is an end view of a part of the machine; and

Fig. 12 is a sectional view through one of the slides in the machine.

The machine illustrated as an embodiment of the principles of the invention comprises a base 11 with a standard 12 from which extend lateral arms 13 and 14. Mounted in a bearing in the standard and extending through the lower arm 14 is the main drive shaft 15, the shaft being supported at its free end in a bearing 16 mounted in a standard 17 projecting upwardly from the base. A drive pulley 18 is mounted loosely on the drive shaft and is movable lengthwise of the shaft by means of a channeled collar 19 on the shaft 20 movable along the latter by a bell crank 20. The pulley carries the male member 21 of a clutch which cooperates with the female member 22 keyed to the shaft and secured to the face of the clutch member 22 is a gear 23 which drives gear 24 on cam shaft 25 through an idler gear 26. The cam shaft 25 extends through the arm 13 of the machine and is provided with a hand wheel 27 so that it can be moved to set the machine properly for starting.

The shaft 15 is connected to an aligned shaft 27' by a coupling 28 within the arm 14 and shaft 27' carries a disc 29 on its end which is provided with an eccentric pin 30 having an enlarged head 31. The shaft 27' extends through a bushing 32 in the end of arm 14, the bushing being held in place by a pin 33. Mounted on the end of the bushing 32 and encircling the end flange 34 thereon is a cup shaped element 35, this element constituting a part of the means for supporting and advancing the mesh to be operated on.

The element 35 as illustrated in Figs. 5 and 8 is provided with a plurality of pockets 36 therein and around each pocket at a spacing of 90° are upstanding pins 37, other pins 38 being disposed along the edges of the element in alignment across the face of the latter with pins 37 which lie between the openings 36.

The arrangement of the openings and pins on the supporting element depends on the character of the mesh which is to be operated on, the openings and pins being so arranged that when a piece of mesh is placed in contact with the support, as illustrated in Fig. 6, a spider 39 will lie above each of the openings 36 and the pins 37 and 38 will extend through rings 40 of the mesh. It will be noted that with the pins 37 arranged at a spacing of 90° about each opening 36, one of those pins

will enter each ring which is attached to the leg of a spider overlying that opening.

Secured to one end of the supporting element by pins 41 is a ratchet wheel 42 and this wheel is acted on by a pawl 43 held against the face of the wheel by a coil spring 44. The pawl is mounted by means of a screw 45 on a plate 46 adjustably mounted in a slide 47. The plate 46 is movable relative to the slide by means of adjusting screws 48 and 49 so that the position of the pawl relative to the ratchet can be exactly determined. The slide 47 is mounted in a recess in the end of the arm 14 and is held in place in that recess by the face of the ratchet wheel 42. The slide is provided with a vertical slot into which projects a pin 50 eccentrically mounted in the end of a shaft 51 extending through the arm 14 and driven by a gear 52 meshing with a gear 53 on the main drive 15.

As the shaft 51 rotates the pin causes slide 47 to reciprocate horizontally and in its movement, the slide carries the pawl 43 which engages the ratchet wheel 42 and causes that wheel and mesh support 35 to advance with a step by step motion. The ratchet wheel is prevented from retrograde movement by a spring pressed pawl 54 mounted on a plate 55 secured to the outer surface of the arm 14.

Within the open end of the mesh support 35, the bushing is provided with projections 32' providing guideways for a pair of slides 56 and 57. The slide 56 carries a tool 58 in its upper end and has an opening 59 elongated horizontally for receiving the eccentric pin 30. As shaft 27 is rotated, the eccentric movement of the pin causes slide 56 to move up and down and tool 58 passes through one of the openings 36 in the support at the end of its extreme upper movement. The pin strikes a spider in registry with the opening and deforms the spider, after which the latter is forced from the mesh into the opening by other means.

The slide 57 provides a means for clearing the deformed spiders from the openings and this slide has an opening 60 elongated horizontally through which the pin 30 extends. The slide carries an ejector pin 61, mounted in a block 61' pinned in the slide and as the eccentric pin revolves, the slide 57 is reciprocated horizontally and at the extreme limit of its movement in one direction, pin 61 passes through an opening 36 in the support and forces out the deformed spider which has been deposited therein. The spider is then acted on by an air blast issuing from the pipe 62 and blown into a discharge chute 63.

The mesh to be operated on is fed upwardly by the operator along a plate 64 which has an opening through which a portion of the top of the support 35 extends and the mesh is held in contact with the support by means of a foot 66 on the end of a plunger 67 in a cylinder 68. A spring 69 within the cylinder forces

the plunger downwardly and the plunger is provided with a pin 70 extending through a slot 71 in the side of the cylinder so that the foot can be raised and held clear of the mesh 5 against the action of its spring.

The cam shaft 25 extends through a bushing 72 in the end of the arm 13 and this bushing lies within a tubular extension 73 from cam housing 74. The cam housing is held in 10 place in the end of the arm 13 by means of a pin 75.

Within the cam housing is a cam disc 77 secured against rotational movement on the end of the shaft 25 by means of a key 78.

15 The cam disc has a cam slot 79 in its face and into this slot projects a roller 80 on an extension from a slide 81. Slide 82 also has a roller 83 entering the slot 79. The slide 81 has a portion 84 freely movable within a recess 85 in the end of the slide 82. Threaded in the other end of the slide 82 is a threaded adjusting block 86 which enters a slide 87 which has an opening in its end in which is mounted the tool 88. The slide 81 is provided 20 with an ejector rod 89 which extends through aligned openings in slide 82, block 86, slide 87, and tool 88. The cam disc 77 which is movable endwise relative to the shaft 25 is held in place by means of a cover 90. The 25 surface of this cover forms part of a guideway for slides 81, 82, and 87, the guideway being completed by a cover plate 91 and there is an opening 92 in the cover plate 91 through which a tool may be applied to the body 93 30 of the block 86 to provide a delicate adjustment of the slide 87 relative to slide 82.

35 The tool 88 is secured in the end of the slide 87 by means of a holding screw 94 and this tool is provided at its free end with four 40 prongs 95. The shape and spacing of these prongs depend upon the type of mesh that is being operated on and the purpose of the tool is to engage the mesh at four sides of the spider which is to be removed so as to prevent movement of the mesh during deformation 45 of the spider. As illustrated in Fig. 6, each prong 95 of the tool is so positioned as to overlie two of the four rings with which the legs of the spider to be removed are engaged 50 and the edge of each prong slightly overlies the edge of the plate portion of the spider but does not interfere with that portion being distorted in connection with its removal.

55 In the operation of the device, the hand wheel 27 is rotated to turn the shafts to an extent such that the various slides driven thereby are retracted and out of operative position. The operator then places a piece of mesh on the feed plate 64 and slides the mesh up so that its forward edge overlies the rotary supporting element 35. The operator then adjusts the mesh so that the pins 37 and 38 on the support enter rings in the mesh and the spiders which are to be removed lie in registry 60 with the openings 36 through the support.

The foot 66 is next let down on the top of the mesh so as to hold it in contact with the support. The clutch is now thrown in and the machine driven by power.

In the operation of removing a spider, the slides 82 and 87 are moved downward so as to bring the prongs 95 in the end of the tool 88 into contact with the mesh on all four sides of the spider to be removed, the tool passing through an opening formed in the foot for this purpose. The position of the tool in the slides is accurately adjusted so that when it is dropped down it holds the mesh firmly at the four points mentioned without crushing or doing injury to the mesh. Immediately after the contact of the tool with the mesh, the slide 56 moves upward and tool 58 on its upper end passes through an opening 36, engages the flat surface of a spider, and deforms the spider so that it assumes the shape illustrated at 96. In this deformation of the spider, its legs 97 are sprung apart slightly. The slide 56 is now retracted, moving its pin 58 away from the under side of the spider, and immediately thereafter slide 81 is moved downward and the ejector rod 89 carried therein engages the deformed surface of the spider between the legs and forces the spider down into the pocket 36. In this operation, the legs are sprung clear of the links through which they extend. The ejector rod 89 is mounted with a screw adjustment 98 in the slide 81 so that the pin may be exactly positioned to perform its functions. As soon as the deformed spider has been removed from the mesh in the manner described, the tool 88 and rod 89 are raised clear of the mesh and the mesh support 35 is advanced by another step to bring the spider in registry with the next opening 36 into alignment with pin 58 and tool 88.

100 The deformed spiders 96 removed from the mesh in the manner described remain in the pockets 36 until the support has made a quarter turn, in which position, the pocket in which the spider is carried lies in alignment with the ejector pin 61 on the slide 57. During the period of rest in which the pocket carrying the deformed spider is in registration with the pin 51, slide 57 is moved to cause pin 51 to enter the pocket and force the deformed spider out in the path of the air blast 62.

105 110 115 120 125 The mesh from which the spiders have been removed is carried away from the surface of the support 35 on an extension 99 of the feed plate 64 so that at the time the deformed spiders are removed from the pockets, the mesh is clear of the pins on the support adjacent these pockets.

120 It will be seen that in the operation of the machine, the mesh is positively supported and fed to operating position with a step by step movement and in the periods of rest of that movement, the mesh is held firmly 125

against the support by means of the tool 88, this tool making contact with the mesh at spaced points closely adjacent to the spider that is to be removed. This spider is then 5 deformed by the tool 58 and removed from the mesh by the ejector rod, the tool and rod also operating in the period of rest of the mesh. Similarly, the ejector pin 61 which 10 discharges the deformed spiders from the pocket operates in the period of rest of the mesh.

The machine operates at high rates of speed and has been regularly driven at a speed such that 600 spiders are removed per 15 minute. After the machine is in operation, the operator performs no duties other than to see that the mesh lies smoothly on the feed plate 64, the movement of the mesh being accomplished by means of the rotary support 35.

When the machine is used for removing spiders from bias rows in the fabric, the mesh discharged from the machine still contains rings which are left behind in those rows. 25 These rings can then be easily cut by means of shears to separate the two pieces of mesh.

I claim:

1. A machine for removing links from link mesh fabric which comprises the combination of means for advancing a piece of the fabric, means for holding the mesh adjacent the link to be removed, means for distorting said link, and means for forcing the distorted link from the fabric.

2. A machine for removing links from link mesh fabric which comprises the combination of means for supporting and advancing a piece of the fabric, means for holding the fabric adjacent the link to be removed, means for distorting said link, and means for forcing the distorted link from the fabric.

3. A machine for removing links from link mesh fabric which comprises the combination of means for supporting and advancing a piece of the fabric, means cooperating with the supporting means for holding the fabric adjacent the link to be removed and means for forcing said link from the fabric.

4. A machine for removing links from link mesh fabric which comprises the combination of means for advancing a piece of fabric, means for holding the fabric adjacent the link to be removed, and means for removing said link from the fabric.

5. A machine for removing links from link mesh fabric which comprises the combination of means for advancing a piece of fabric, means for holding the fabric adjacent the link to be removed, and means for distorting said link and forcing it out of the fabric.

6. A machine for removing links from link mesh fabric which comprises the combi-

nation of means for advancing a piece of fabric with a step by step movement, means operative in the periods of rest of said movement for holding the fabric adjacent the link to be removed, and means operative during said periods for removing said link from the fabric.

7. A machine for removing links from link mesh fabric which comprises the combination of means for supporting and advancing a piece of fabric with a step by step motion, means cooperating with the supporting means for holding the fabric adjacent the link to be removed, and means for removing said link from the fabric.

8. A machine for removing links from link mesh fabric which comprises the combination of an element movable step by step for supporting and advancing a piece of fabric, means cooperating with the element for holding the fabric against the support to prevent movement of the fabric relative to the supports, said means engaging the fabric adjacent the link to be removed, and means for removing said link from the fabric.

9. A machine for removing links from link mesh fabric which comprises the combination of a rotary element for supporting and advancing a piece of fabric, means for rotating the element step by step, means operative during the periods of rest of said movement for holding the piece of fabric in place on said element, and means operative during said periods of rest for removing links from said fabric.

10. A machine for removing links from link mesh fabric which comprises the combination of an element for supporting and advancing a piece of fabric, means cooperating intermittently with said element to hold the piece of fabric against movement relative to said element and means for removing links from said fabric adjacent the place where it is held.

11. A machine for removing links from link mesh fabric which comprises the combination of an element for supporting and advancing a piece of fabric, means cooperating with the element to hold the piece of fabric against movement relative to said element, said holding means acting on portions of the fabric around the link to be removed, and means for removing said link from the fabric.

12. A machine for removing links from link mesh fabric which comprises the combination of an element for supporting and advancing a piece of fabric, means cooperating with the element to hold the piece of fabric against movement relative to said element, said holding means acting intermittently and engaging portions of the fabric around the successive links to be removed, and means for removing said links successively from the

- fabric while surrounding portions of the fabric are being held.
13. A machine for removing links from link mesh fabric which comprises the combination of a rotary element for supporting and advancing a piece of mesh fabric, said element having openings registering with the links to be removed from said piece, means operating to hold the fabric against the support, said means engaging the fabric around said openings, means within the element movable through said openings to deform the links in registry therewith, and means for removing said deformed links from said fabric.
14. A machine for removing links from link mesh fabric which comprises the combination of a rotary element for supporting and advancing a piece of mesh fabric, said element having openings registering with the links to be removed from said piece, means operating to hold the fabric against the support, said means engaging the fabric around said openings, means within the element movable through said openings to deform the links in registry therewith, means for moving said deformed links from said fabric and into said openings, and means for ejecting said links from said openings.
15. A machine for removing links from link mesh fabric which comprises the combination of a rotary element for supporting and advancing a piece of mesh fabric, a member cooperating with the element for holding the piece of fabric against movement relative to said element, a tool operative to engage successive links in the fabric and deform said links, and an ejector acting on said deformed links and forcing them from the fabric.
16. A machine for removing links from link mesh fabric which comprises means for supporting and advancing a piece of link mesh fabric, means engaging said fabric to prevent its movement relative to said support, and means for removing links from said fabric while it is thus supported and held.
17. A machine for removing links from link mesh fabric which comprises means for supporting and advancing a piece of link mesh fabric, means engaging said fabric to prevent its movement relative to said support, and means for removing links from said fabric while it is thus supported and held, said supporting and advancing means operating to advance said fabric with a step by step movement, and said removing means operating during the periods of rest of said movement.
18. A machine for removing links from link mesh fabric which comprises the combination of a support for a piece of mesh movable to advance the latter, means for holding the mesh on said support, a tool operable to engage successive links in the mesh and deform them to facilitate their removal, and an ejector engaging the deformed links and removing them from the mesh.
19. A machine for removing links from link mesh fabric which comprises the combination of a support for a piece of mesh movable to advance the latter, means for holding the mesh on said support, a tool operable to engage successive links in the mesh and deform them to facilitate their removal, an ejector engaging the deformed links and moving them from the fabric into recesses in the support, and means for removing the links from the recesses.
20. A machine for removing links from link mesh fabric which comprises the combination of a support for a piece of mesh movable to advance the latter, a member cooperating with the support to hold the mesh against movement thereon, a tool movable through the openings in the support to engage links in the fabric and deform them to facilitate their removal, and an ejector carried by said member and operative to force said deformed links from the mesh.
21. A machine for removing links from link mesh fabric which comprises the combination of a support for a piece of mesh movable to advance the latter, a member cooperating with the support to hold the mesh against movement thereon, a tool movable through the openings in the support to engage links in the fabric and deform them to facilitate their removal, an ejector carried by said member and operative to force said deformed links from the mesh and into said openings, and means for removing said links from said openings.
22. In a machine for removing links from link mesh fabric the combination of a rotary element for supporting and advancing a piece of mesh, said element having openings through it to expose links in the piece of mesh, a member movable toward and away from the support and in its advanced position engaging the mesh on the support and holding it against movement, a tool within the support operable through said openings successively to deform the link exposed in each opening, and an ejector plunger in said member operable to force the deformed link from the mesh.
23. In a machine for removing links from link mesh fabric, the combination of a tool having mesh holding means at its end and provided with an ejector movable relative to the remainder of the tool, a second tool having an end shaped to deform a link, means for supporting and advancing a piece of mesh between the tools with a step by step motion, and means operating the tools in the periods of rest of the mesh to cause them to hold the mesh, deform a link therein, and eject the deformed link.
24. In a machine for removing links from link mesh fabric which comprises the combination of a support for a piece of mesh movable to advance the latter, means for holding the mesh on said support, a tool operable to engage successive links in the mesh and deform them to facilitate their removal, and an ejector engaging the deformed links and removing them from the mesh.

link mesh fabric, a holding and ejecting tool comprising a body terminating in spaced members shaped to engage portions of a piece of mesh around a link to be removed, and a plunger in the body aligned with the middle of the space between said members and movable into and out of the body.

25. In a machine for removing spiders from fish-scale mesh, a cylindrical support for the mesh having openings spaced to underlie spiders in a row in the mesh and pins entering rings in the mesh, means for advancing the support with a step by step movement, a tool movable toward and away from the support for engaging rings in the mesh connected to the spider to be removed and holding those rings firmly against the support, a tool movable through an opening in the support to engage and deform said spider, an ejector operable to force the deformed spider from the mesh and into said opening, and means for removing the spider from said opening.

In testimony whereof I affix my signature.
FRED H. LYNDS.
